SKI EDGE

William F. Serr, New York, N. Y., assignor, by
mesne assignments, to Eric Pusinelli, New York,
N. Y.

Application March 26, 1941, Serial No. 385,248

7 Claims. (Cl. 280—11.13)

The invention relates to skis and more particularly to metal reenforcing strips commonly known as ski edges.

According to one form which the invention may assume, the ski edge is made up of sections or lengths, each section comprising an inner and an outer strip suitably welded together. The inner strip has spaced keyhole slots, the narrow ends of which are beveled and undercut to seat level headed screws. The outer strips have holes in line with the screws but of smaller diameter than the screw heads, through which a screw driver may be inserted for driving the screws home. Extra holes may be provided in the inner strip for flexibility and the holes in the outer strip may be suitably filled up with plastic after the edge is mounted on the ski. If desired, the ends of the inner strips may be provided with notches on one end and tongues on the other, which interfit to assist in aligning and locking the sections of ski edge. Furthermore, if desired, the side walls of the laminated ski edges may be hollow ground to provide sharper corners on the outer edges of the ski edge to reduce side slipping.

The ski edge sections may be made either with the tongues facing forward or backward. In the event the tongues face forward, a natural shingle effect is obtained, insuring absence of any forward facing transverse edges or ribs on which the snow may catch and slow up the ski. In the event the tongues face backward, it is desirable to place the screws close to the forward ends of the sections to insure holding down tight the forward ends of the sections which overlap the rear tongues to prevent catching on the snow and slowing down the ski.

In some cases the outer and inner lamination of the ski edge may be separable, the inner strip being permanently fastened to the ski by suitable screws passing through longitudinal slots. The inner strip may have suitable keyhole slots and the outer strip may be provided with integral beveled projections which cooperate with the keyhole slots to hold the outer strips in position.

The invention also consists in certain new and original features of construction and combination of parts hereinafter set forth and claimed.

Although the novel features which are believed to be characteristic of this invention will be particularly pointed out in the claims appended hereto, the invention itself, as to its objects and advantages, and the manner in which it may be carried out, may be better understood by referring to the following description taken in con-

nection with the accompanying drawings forming a part thereof, in which

Fig. 1 is a fragmentary plan view of the bottom of a ski equipped with my invention;

Fig. 2 is a plan view illustrating several sections of my ski edge detached from the ski, locking at the side of the edge which faces the ski;

Fig. 3 is a plan view of a section of my ski edge, looking at the outer side thereof or that surface which contacts the snow;

Fig. 4 is a greatly enlarged fragmentary section taken on the line 4—4 of Fig. 1;

Fig. 5 is a fragmentary perspective showing the manner of interlocking two adjoining sections of ski edge;

Figs. 6, 7 and 8 are transverse sections taken on the lines 6—6, 7—7 and 8—8 of Fig. 4;

Fig. 9 is a fragmentary side elevation of a ski showing the manner of applying my edge to the ski;

Fig. 10 is a view corresponding to Fig. 2, but of a modified form of ski edge;

Fig. 11 is a side elevation showing the ski edge of Fig. 10 attached to a ski;

Fig. 12 is an enlarged, fragmentary, bottom plan view of still another embodiment of my invention;

Fig. 13 is a longitudinal cross-sectional view taken along the line 13—13 of Fig. 12;

Fig. 14 is a transverse cross-sectional view taken along the line 14—14 of Fig. 13;

Fig. 15 is a perspective, fragmentary view of the two interlocking strips illustrated in Figs. 12—14 inclusive, indicating the method of assembling these strips;

Fig. 16 is a fragmentary, transverse, cross-sectional view illustrating a modification of the edge construction of Fig. 12; and

Fig. 17 is a transverse cross-sectional view illustrating an application of the construction of Figs. 12—14 to a center insert strip.

In the following description and in the claims, various details will be identified by specific names for convenience, but they are intended to be as generic in their application as the art will permit.

Like reference characters denote like parts in the several figures of the drawings.

In the drawings accompanying and forming part of this specification, certain specific disclosure of the invention is made for purposes of explanation, but it will be understood that the details may be modified in various respects without departure from the broad aspect of the invention.

Referring now to the drawings and more par-

ticularly to the form of the invention shown in Figs. 1-9, inclusive, the reference character 10 denotes the body of a conventional ski which has applied thereto along the lateral edges thereof the metallic sectional edge strips indicated by 11. These edge strips or ski edges are made up of a base strip 12, which is preferably constituted of a strip of steel easily machined, and is provided at spaced intervals with keyhole slots 13 and holes 14.

A second, outer strip, preferably of hard tempered steel, denoted by 15, and having holes 16, is superimposed upon the strip 12 and the two strips 12 and 15 are suitably attached together as by spot welding at points indicated by 19. This assembly of the two steel strips makes up a unitary structure, a plurality of which are arranged in line and fit together to form the continuous ski edges 11, as will be understood by those skilled in the art.

It will be noted that the outer strips 15 have straight ends which directly abut (see Fig. 5) while the inner or base strips 12 have cooperating notches 17 on one end into which fit tongues 18 on the other end. These cooperating tongues and notches assist in assembling the ski edges and in holding the sections thereof in alignment.

The bayonet slots 13 have a narrower end 21 beveled, as indicated by 22, to fit the beveled heads of screws 23. The larger parts of the bayonet slots 13 are of substantially the same width as the wider sides of the beveled portions 22. The holes 16 in the outer bars 15 are beveled at their inner and outer edges as denoted by 24, for a purpose hereinafter described, and the minimum diameter of the holes 16 is approximately equal to the minimum dimension of the beveled portions 22 of the keyhole slots.

The side walls or edges of the sectional strips 11 may be hollow ground as denoted by 25 and 26 (Figs. 6-8) to smooth off these edges and to make sharper corners to insure less side slipping of the ski on the snow.

To apply the ski edges to the wooden ski, the latter is first channeled as indicated by 27 (Figs. 6-8) and is then provided with a plurality of drill holes 16' corresponding to the holes 16, using the ski edge as a templet if desired. The screws 23 are then placed in their keyhole slots 13 by inserting the heads in the wide portions thereof and sliding the screws lengthwise of the slots to snugly engage the bevel portions 22, the assembled edge and screws being indicated in Fig. 9.

This edge is assembled from front of ski to rear, a front section A being indicated already in position in Fig. 9. To apply the succeeding edge assembly indicated by B in Fig. 9, it is only necessary to insert the screws in their respective holes in the ski and screw the screws home into the wood, the holes 16 permitting access of the screw driver into the screw driver slots in the screw heads. The end of the outer bar 15 of section B (Fig. 9) overlies the tongue 18 of the adjacent section A, the tongue 18 fitting into the notch 17.

In the same way the successive sections of ski edge will be applied until the desired length is equipped, after which the holes 16 may be plugged up with plastic wood, or cement, or ski wax, the inner bevel portion 24 assisting in holding the plastic filler material in position.

Referring now to the modification shown in Figs. 10 and 11, this construction is quite similar

to the ski edge above described, the ski body here being denoted by 39, the inner strip by 31, the outer strip by 32. The holes in the inner strip are denoted by 33, the keyhole slots by 34, 5 the holes in the outer strip by 35 and the screws by 36. The inner strips have notches 37 in one end, which receive tongues 38 in the other end of the adjoining strips and the strips are welded together at the points indicated by 39, as in the preceding form.

The form illustrated in Figs. 10 and 11 is applied to the ski very much like the form above described, except that the strips are applied from the rear of the ski toward the tip. This form has 15 the advantage that the ends of the strips overlying the tongues 38 are forward of the adjoining ends, so that any misalignment or defect which may cause the surface of the overlying end to protrude slightly above the surface of the adjoining section will not interfere with the smooth running of the ski, since as the ski slides on the snow, a "shingle effect" is obtained, this effect being similar to the shingle effect of water sliding down a shingled roof of a house. This effect 20 is indicated in somewhat exaggerated degree at C in Fig. 11.

The principal difference between the form shown in Figs. 10 and 11 and the form first described is the fact that the screws are not located so close to the ends in Figs. 10 and 11 and in Figs. 1-8. In Figs. 1-8 the screws are located close to the ends for the purpose of positively holding down these overlying ends and preventing any raising of the ends which might 30 catch on the snow and slow up the ski. This precaution is not necessary in Figs. 10 and 11 in view of the "shingle effect" above described. In each case it will be seen that the narrow part of the keyhole slots faces forward so that the 35 drag of the snow on the ski edge will always tend to keep the screws tightly engaged in the narrow ends of the keyhole slots.

The construction above described has many advantages which will be obvious to skiers and 45 ski repair men. The outer or running strip of the composite ski edge having holes smaller in diameter than the screw heads actually forces the screws in during skiing instead of allowing them to loosen and fall out. The beveled edges of the holes on the outer strips insures the removal of burrs on the outer surface of the ski and helps retain the filled-in plastic wood or hard wax. The beveled keyhole slots effect a fastening to the screws and yet permit play for contraction and expansion of the ski edge. The holes between the keyhole slots lighten the ski edge and make it more flexible.

The drilling and centering of the screw holes may be accomplished by using the edge itself as a templet before the screws are inserted, and speedy attaching is obtained by assembling the screws and the edges first before attaching to the ski. The holes in the outer strips permit access of the screw driver to the screws for easy assembly. The tongues and notches assist in aligning up the adjoining sections and hold them in firm interlocked relation. The hollow ground construction of the side edges not only insures smooth edges, but also sharpens the corners, decreasing side slipping.

Referring now particularly to Figs. 12 to 17, inclusive, there is illustrated still another embodiment of my invention. In this embodiment, the base strip is provided with T-slots and the top or outer strip is provided with lugs or the like for

detachably connecting the top or outer strip to the base strip.

The wooden ski 100 is provided with channeled edges 112, as illustrated, and a metallic base strip 101 is inserted in each edge and is secured to the ski by screws 102 extending through suitably arranged, countersunk elongate openings 103 in the base strip 101. Each base strip 101 thereby is securely and more or less permanently secured to the ski.

The elongate openings 103 are beveled along their longitudinal edges to fit the screw heads as shown but are sufficiently long to provide room for two or more screws. This is of advantage in requiring less accuracy in drilling the holes in the wooden ski 100 to take the screws 102 and also provides room to put a second screw in the same hole if for any reason it is desired to do so, as for example, if the first screw breaks.

The base strip 101 is provided with a plurality of spaced, keyhole slots 105 each of which is provided with an enlarged portion 106 and a narrow portion 107. The side walls of the narrow portion 107 are divergent as illustrated particularly in Fig. 14. The base strip may be provided, if desired, with a plurality of openings 104 for the purpose of reducing the weight of the strip and rendering it more flexible.

A metallic top or outer strip 110 is provided and has a plurality of lugs 111 projecting therefrom at locations so disposed as to register with the enlarged portions of the keyhole slots 105 of the base strip 101 when the two strips are superposed. The lugs 111 may be formed in any suitable manner and may be constituted by rivets, or screws, or may be formed as integral portions of the top or outer strip 110. The lugs 111 are so positioned and are of such size that they enter the enlarged portions 106 of the keyhole slots 105 and upon movement of the strip 110 toward the rear of the ski longitudinally of the strip 101, the lugs 111 enter and are firmly gripped by the narrow portions 107 respectively of the slots. Thus the top or outer strip 110 is locked securely in position.

In Fig. 16 there is illustrated a modification of the construction of Figs. 12 to 15, inclusive. In this embodiment of the invention the wooden ski 120 is provided with a channeled portion 128 which receives a base strip 121 generally similar in construction to the base strip 101 above described. However, the base strip 121 has secured thereto or formed as an integral part thereof a flange or extension 122 which has an outer edge generally flush with the outer edge of the base strip 121. Where the extension 122 is separately formed and is secured to the base strip 121 it may be secured by welding as indicated by the reference character 123.

It will be seen that the extension 122 provides with the opposite edge of the paneled portion 128 of the ski a seat for a top or outer strip 124 which may be formed from non-metallic material such as an artificial resin, and preferably a fabric-reinforced artificial resin. The top or outer strip 124 may be provided with a plurality of lugs 126 which may be constituted by screws threaded into the strip 124. The lugs 126 then function in a manner generally analogous to the lugs 111 above described for the purpose of securing the top or outer strip 124 to the base strip 121.

The inventive concept illustrated by Figs. 12 to 15, inclusive, may be applied to a center strip or insert as illustrated particularly in Fig. 17. The wooden ski 130 is provided with a central channel

132 in which is disposed a base strip 131 constructed generally like the base strip 101 above described. The top or outer strip 135 is secured to the base strip 131 by means of lugs 134 which are inserted in and cooperate with keyholes 133 in the base strip 131. As illustrated in Fig. 17, the base strip 131 or top or outer strip 135 may be of somewhat larger and heavier construction than the strips 101 and 110 respectively which are employed at the side edges of the ski. However, it will be understood that the general construction and function of the strips 131 and 135 are in general similar to the construction and function of the strips 101 and 110 above-described.

It is obvious, furthermore, that other adaptations of the means herein disclosed for attaching the protective edge strips may be also employed to attach the intermediate strips.

While certain novel features of the invention have been disclosed and are pointed out in the annexed claims, it will be understood that various omissions, substitutions and changes may be made by those skilled in the art without departing from the spirit of the invention.

What is claimed is:

1. In a ski, a body member, a reenforcing strip comprising a plurality of sections of laminated metal, each section having a base strip with means for attaching to the ski body and an outer strip for running on the snow, each inner strip having at one end a notch and at the other end a tongue, the adjoining strips substantially abutting with the ends on the outer strips in engagement and the tongues on the inner strips seated in the notches of the adjoining inner strips, said tongues projecting from the ends of their respective sections and seated under the ends of the adjoining sections.

2. A ski edge comprising an inner strip and an outer strip secured together, said inner strip having spaced openings, screws in said openings, said openings having a dimension smaller than the screw heads whereby the screws may attach said ski edge to a ski body, said outer strip having holes in line with said screws, the minimum diameter of said holes being less than the maximum diameter of said screw heads, whereby said screws and ski edge may be pre-assembled before attaching to a ski and said outer strip holes permit access of a screw driver to drive the screws into the ski body.

3. A ski edge comprising an inner strip and an outer strip secured together, said inner strip having spaced beveled openings, bevel headed screws in said openings, said openings having a dimension smaller than the screw heads whereby the beveled heads of the screws may engage the beveled surfaces on said openings and the tops of said screws are substantially flush with the outer surface of said inner strip, said outer strip having holes in line with said screws, the minimum diameter of said holes being less than the maximum diameter of said screw heads, whereby said screws and ski edge may be pre-assembled before attaching to a ski and said outer-strip holes permit access of a screw driver to drive the screws into the ski.

4. A ski edge comprising inner and outer strips secured together in laminated relationship, said inner strip having beveled openings to receive bevel headed attaching screws which go into the body of the ski, said inner strip having openings between the attaching openings to lighten the construction and to improve the flexibility, said outer strip being welded to said inner strip and

engaging over the heads of said screws, said strips being divided into relatively short sections extending, end to end, lengthwise of the ski.

5. A ski edge strip comprising an inner strip and an outer strip welded together, said inner strip having spaced keyhole slots, the narrow portions of said keyhole slots having beveled sides, bevel headed screws seated in the narrow portions of said keyhole slots with their heads against said outer strip, said outer strip having holes in line with said screws, the minimum diameter of said holes being less than the maximum diameter of said screw heads, said outer strip holes having bevel edges to retain filler material, said inner strip having holes intermediate said keyhole slots to increase the flexibility of the composite strip, whereby said screws may be pre-assembled in said keyhole slots and said strips and screws may be applied to the ski as a unit.

6. A ski edge comprising an inner strip and an outer strip welded together, said inner strip having spaced keyhole slots, the narrow portions of

said keyhole slots having beveled sides, bevel headed screws seated in the narrow portions of said keyhole slots with the heads against said outer strip, said outer strip having holes in line with said screws, the minimum diameter of said holes being less than the maximum diameter of said screw heads, whereby said screws may be pre-assembled in said keyhole slots and said strips and screws may be applied to the ski as a unit.

10 7. A ski edge comprising an inner strip and an outer strip secured together, said inner strip having spaced keyhole slots, screws seated in the narrow portions of said keyhole slots with their heads against said outer strip, said outer strip having holes in line with said screws, the minimum diameter of said holes being less than the maximum diameter of said screw heads, whereby said screws may be pre-assembled in said keyhole slots and said strips and screws may be applied to the ski as a unit.

WILLIAM F. SERR.
